UNITED STATES PATENT OFFICE.

JOHN CROY, OF GREENVILLE, MICHIGAN.

EXPANSION-CULVERT.

No. 894,120.

Specification of Letters Patent.

Patented July 21, 1908.

Application filed February 21, 1908. Serial No. 417,066.

To all whom it may concern:

Be it known that I, JOHN CROY, a citizen of the United States of America, residing at Greenville, in the county of Montcalm, and 5 State of Michigan, have invented new and useful Improvements in Expansion-Culverts, of which the following is a specification.

This invention relates to culverts the object of the invention being to provide an 10 expansion culvert, or in other words a culvert made up of a plurality of sections having a jointed, interlocked and movable connection with each other in order to adapt the culvert as a whole to readily accommodate 15 itself to changes in temperature.

With the above general object in view, the invention consists in the novel construction, combination and arrangement herein fully described, illustrated and claimed.

20 In the accompanying drawings:—Figure 1 is an end view of an expansion culvert embodying the present invention. Fig. 2 is a side elevation of a portion of the same. Fig. 3 is a horizontal section taken on the line 25 3—3 of Fig. 1 looking upward.

The culvert contemplated in this invention is composed of three main sections 1, 2 and 3 which, when connected up in the manner shown in Fig. 1, form a transversely 30 complete culvert or conduit which has a smooth interior to permit the free and uninterrupted flow of water therethrough. It will, of course, be understood at this point that each of the sections 1, 2 and 3 may 35 itself be composed of any desired number of sections according to the length of the culvert.

The main or bottom section 1 is by preference curved or slightly dished transversely on its upper side and is provided along both 40 sides with knuckles 4 substantially cylindrical in shape or in the form of hollow sleeves, each of said knuckles being provided along its upper side with a continuous slot 5 which is preferably flared, as shown, to 45 admit of a limited rocking movement of the sides of the culvert as hereinafter more particularly explained.

The side sections 2 and 3 are arched as shown in Fig. 1 and constructed so as to overlap 50 each other at the top, one of the sections being rabbeted as shown at 6 to receive the end of the opposite side section to admit of lateral expansion and contraction.

7 designates lugs secured to one of the side

sections and adapted to extend under the 55 adjacent extremity of the other side section thereby forming a thoroughly braced connection between said sections at the top of the culvert.

Each of the side sections 2 and 3 is provided at its bottom edge with a cylindrical bead 8 adapted to fit into the socket of the knuckle 4 and also adapted to turn therein. The slot 5 has a width greater than the thickness of the body of the side section while the 60 width of said slot is less than the width or diameter of the cylindrical bead 8. This permits the sections 2 or 3 to rock relatively to the bottom section while preventing any 65 possibility of the two sections becoming disconnected one from the other. Thus, an interlock rock-joint is established between the side sections of the culvert and the bottom sections which permits a limited lateral rock- 70 ing movement of the side sections and take 75 care of the expansion and contraction of each and all of the sections both transversely and longitudinally of the culvert.

Under the preferred embodiment of the invention, the sections of the culvert are provided exteriorly with transverse reinforcing ribs 9 which add materially to the strength of the sections and also act to anchor the culvert as a whole against longitudinal slip-page.

By means of the construction above described, a very desirable form of sectional culvert is provided, which does away with all projections upon the interior of the culvert liable to catch and hold refuse, the interior of 90 the culvert being practically smooth and unbroken.

Having described the invention, I claim as new:

A culvert comprising a bottom section 95 provided with knuckles having slots, and side sections provided with cylindrical beads removably fitted in the knuckles, the slots of the knuckles having a width in excess of the thickness of the side sections and less 100 than the diameter of the cylindrical beads.

In testimony whereof I affix my signature in presence of two witnesses.

JOHN CROY.
